CLAIM

I claim the ornamental design for an automobile wheel, as shown and described.

DESCRIPTION

FIG. 1 is a front elevational view of an automobile wheel; and,

FIG. 2 is a perspective view thereof.

The broken lines shown in FIG. 2 illustrate portions of the automobile wheel that form no part of the claimed design. The broken line showing of the rear of the wheel is included for the purpose of illustrating environment and forms no part of the claimed design.
